United States Patent Office.

WILLIAM R. THOMAS, OF CATASSAUQUA, PENNSYLVANIA.

Letters Patent No. 80,030, dated July 14, 1868.

IMPROVEMENT IN STEAM-PUMPS.

The Schedule referred to in these Letters Patent and making part of the same.

TO ALL WHOM IT MAY CONCERN:

Be it known that I, WILLIAM R. THOMAS, of Catassauqua, in the county of Lehigh, and State of Pennsylvania, have invented a new and useful Improvement in Steam-Pumps; and I do hereby declare that the following is a full, clear, and exact description thereof, which will enable others skilled in the art to make and use the same, reference being had to the accompanying drawings, forming part of this specification.

The nature of my invention relates to improvements in double-acting steam-pumps, the object of which is to simplify the construction and improve the efficiency of the same.

It consists in an arrangement, whereby the steam is made to actuate the valves without the intervention of valve-gear; in the construction of the cylinder-heads, having extensions from each end, to serve for the pump-cylinders; in the arrangement of projections from the piston, to serve the purpose of the plungers for the pumps; and in an improved means of packing the pistons of the pumps, as will be more fully described on reference to the accompanying drawings, whereina—

Figure 1 represents a side elevation, partly in section, and

Figure 2 a cross-section, on the line $x x$, of fig. 1.

Similar letters of reference indicate corresponding parts.

A represents a steam-cylinder, of which the heads, B, are provided with the prolongations C C, forming the barrels or cylinders of force-pumps. D represents the steam-piston, provided with the cylindrical prolongations E E, constituting the plungers of the pumps. F represents the valve-chest, and G the valve-piston, provided with the chambers a and a' . $b b'$ are the induction-ports, $d d'$ the ejection-ports, and $e e'$ represent ports for opening communication from the steam-cylinder to the chambers a and a' in the valve-piston, for actuating the same, to operate the piston D. The port e communicates with the chamber a' , and the port e' with the chamber a .

The steam, being admitted from the chamber F, through the port b' , to the right side of the piston D, will, the other end of the cylinder being open through the port z to the exhaust, move the said piston to the end of the cylinder at the left, uncovering the port e to the live steam of the cylinder, which, rushing into the chamber a' , will throw the valve-piston also to the left, closing the induction-port b' and the exhaust-port d' , when the piston D will be driven back again to the right until the port e' is uncovered to the live steam of the cylinder, when the piston-valve will again be thrown into the position shown in the drawing, and the piston will be again thrown into motion towards the left.

The prolongations of the cylinder-heads B are pierced with four openings, as shown in the sectional figure, and the heads are provided with lugs, having set-screws arranged to work therein. g represents rubber or other similar packing, made in sections, to fit the said openings, and grooved on the inside, to fit the plungers E. h represents followers, which are operated by the set-screws, to tighten up the packing. Springs may be used in place of the bolts or set-screws, if preferred.

It will be readily perceived that my improvement greatly simplifies and cheapens the construction of steam-pumps, in dispensing with the ordinary valve-gear, separate connection of the pumps, and the usual connecting-rod and crank-shaft, for the connection with the piston-rod.

I claim as new, and desire to secure by Letters Patent—

The arrangement of the ports $e e'$ with relation to the cylinder A, the chambers $a a'$, valve G, induction-ports $b b'$, and the ejection-ports $d d'$, all operating as described, for the purpose specified.

The above specification of my invention signed by me, this 14th day of March, 1868.

WILLIAM R. THOMAS.
